UNITED STATES PATENT OFFICE.

LOUIS J. KOLB, OF PHILADELPHIA, PENNSYLVANIA.

DESIGN FOR BREAD.

SPECIFICATION forming part of Design No. 25,934, dated August 11, 1896.

Application filed September 9, 1895. Serial No. 562,008. Term of patent 3½ years.

To all whom it may concern:

Be it known that I, LOUIS J. KOLB, a citizen of the United States, residing at Philadelphia, in the county of Philadelphia and State of Pennsylvania, have invented and produced a new and original Design for Bread, of which the following is a specification, reference being had to the accompanying drawings.

10 In the drawings, Figure 1 is a perspective view of my design. Fig. 2 is a side elevation of the same.

15 The leading feature of my design consists in the loaf of bread provided with raised scallops or corrugations on the top thereof and

having vertical sides, flat base, and slightly-curved end walls, the whole as shown in the drawings.

A represents the loaf of bread, and B the raised scallops or corrugations which are formed on top of the loaf.

What I claim is—

The design for a loaf of bread herein shown and described.

In testimony whereof I affix my signature in presence of two witnesses.

LOUIS J. KOLB.

Witnesses:

LEWIS H. FRENCH,
G. A. SCHWAB.
